ATTORNEY.

UNITED STATES PATENT OFFICE.

WILLIAM HENRY SAUVAGE, OF DENVER, COLORADO, ASSIGNOR OF TWO-THIRDS TO HENRY NEWTON WOOD AND CHARLES C. WELCH, OF SAME PLACE.

AUTOMATIC BRAKE-BLOCK.

SPECIFICATION forming part of Letters Patent No. 654,809, dated July 31, 1900.

Application filed November 13, 1899. Serial No. 736,788. (No model.)

To all whom it may concern:

Be it known that I, WILLIAM HENRY SAUVAGE, a citizen of the United States of America, residing at Denver, in the county of Arapahoe and State of Colorado, have invented 5 certain new and useful Improvements in Automatic Brake-Blocks; and I do declare the following to be a full, clear, and exact description of the invention, such as will enable others skilled in the art to which it 10 appertains to make and use the same, reference being had to the accompanying drawings, and to the figures of reference marked thereon, which form a part of this specification.

15 My invention relates to improvements in automatic brake-blocks; and it consists of the features hereinafter described and claimed, all of which will be fully understood by reference to the accompanying drawings, in 20 which is illustrated an embodiment thereof.

In the drawings, Figure 1 is a vertical longitudinal section taken through my improved automatic brake-block, the parts being shown in the normal position. Fig. 2 is a similar 25 section of the device, the parts being shown in the position when the brake is applied. Fig. 3 is a front view of the device with the parts in the position shown in Fig. 1. Fig. 4 is a rear view of the brake-shoe shown in 30 detail. Fig. 5 illustrates a toggle-link, two views being shown.

Similar reference characters indicating corresponding parts in these views, let the numeral 5 designate the brake-beam adapted to 35 swing back and forth in proximity to the car-wheel. (Not shown.) To this brake-beam is secured, by means of a bolt 6, the head 7, the bolt being passed through coinciding apertures formed in the beam and a rearward projection 7^a of the head. The front face of the head is provided with a groove 8. Extending 40 rearwardly from this groove is a curved recess which forms a bearing for the rear extremity of a toggle-link 9, which is held in place by a bolt 10, passed transversely through 45 registering apertures formed in the head and the link extremity. The rear extremity of the link is curved to fit the bearing in the head. The forward extremity of the link is 50 also curved to fit a counterpart recess 12, formed in the rear side of the shoe 13. The

link extremity is connected with the shoe by passing a pin 14 through registering openings formed in lugs 13^a and the forward extremity of the link. The lugs 13^a project rearwardly 55 from the rear side of the shoe and are located on opposite sides of the recess 12.

In the upper part of the groove 8 of the head, which is properly shaped for the purpose, is located a stop-cushion 15, supported in any 60 suitable manner. A horizontal shoulder formed at the upper extremity of the groove prevents the cushion from moving bodily upwardly when engaged by the toggle-link when the shoe reaches its upward limit of movement. 65

Each extremity of the head 7 is provided with an inclined face 7^a, which engages an inclined face 13^c, formed on the rear side of the shoe, the said faces being arranged to throw 70 the shoe outward toward the wheel of the car as the shoe is moved upwardly.

The operation of my improved brake-block is as follows: Assuming that the parts are in the position shown in Fig. 1, the brake-beam 75 is moved forward sufficiently to bring the front face of the shoe in contact with the tread of the car-wheel. As soon as this occurs the friction between the wheel turning in the direction indicated by the arrows in Figs. 1 and 80 2 and the shoe raises the latter, and as it moves upwardly the toggle-link co-operates with the inclined faces 13^c and 7^a of the shoe and the head to force the shoe outwardly against the tread of the wheel, setting the 85 brake. The stop-cushion 15, engaging the link, limits the upward movement of the shoe. This cushion may be composed of rubber or other suitable yielding material.

Having thus described my invention, what 90 I claim is—

1. An automatic brake-shoe composed of two members, namely, a head and a shoe movable thereon, the two members being provided with co-operating inclined engaging 95 faces located at each extremity and simultaneously active during the brake-applying operation.

2. A brake-block composed of two members, namely, a head and a shoe movable thereon, 100 the two members being provided with co-operating inclined engaging faces located at each

extremity and an intermediate toggle connection substantially as described.

3. A brake-block composed of a head and a shoe movable thereon and provided with inclined engaging faces, the head being grooved on its front face, and a toggle-link located in said groove and connecting the head and the shoe in operative relation.

4. A brake-block composed of a head and a shoe movable thereon, the head being grooved on its front face, and a centrally-located tog-

gle-link connecting the head and the shoe, the two members being provided with co-operating inclined faces located at each extremity, and arranged to coöperate with the toggle-link for the purpose set forth.

In testimony whereof I affix my signature in presence of two witnesses.

WILLIAM HENRY SAUVAGE.

Witnesses:

GRACE MYTINGER,
A. J. O'BRIEN.
